APPARATUS FOR PURIFYING STEAM

Martin Frisch, New York, N. Y., assignor to Foster Wheeler Corporation, New York, N. Y., a corporation of New York

Application August 31, 1940, Serial No. 354,932

6 Claims. (Cl. 261—23)

This invention relates to steam generators and more particularly pertains to the purification of steam.

The invention provides novel apparatus for the washing and drying of steam in a steam drum of a steam generator whereby the steam will be purified before being superheated or conducted to the point of use.

One advantage of the invention is that the flow of steam and water through the washing apparatus is in the same general direction at very low velocities which results in an improved washing action. In the more conventional horizontal type of bubble tray steam washers, the steam and fresh feed water flow at right angles to each other, and the velocities are necessarily high because approximately but one-third of the tray area is available for steam flow into and out of the washer. With the present invention, practically the entire washer area is available for steam flow, thus making low steam velocities possible. Another advantage of the invention is the accessibility of the apparatus for inspection and cleaning, the arrangement being such that free access through doors provided for the purpose may be had to the interior of the drum and to the washing elements without the need of dismantling any portion of the apparatus.

The invention will be understood from the following description considered in connection with the accompanying drawings forming a part thereof, and in which:

Fig. 1 is a vertical transverse sectional view, taken on line 1—1 of Fig. 2, of a steam drum of a steam generator having one form of apparatus embodying the invention;

Fig. 2 is a vertical longitudinal view of the invention partly in elevation and partly in section on line 2—2 of Fig. 3;

Fig. 3 is a horizontal longitudinal view partly in elevation and partly in section on line 3—3 of Fig. 1;

Fig. 4 is an enlarged transverse vertical sectional view of part of the apparatus;

Fig. 5 is a horizontal longitudinal sectional view taken on line 5—5 of Fig. 4, and

Fig. 6 is a view in perspective illustrating details of the apparatus.

Like characters of reference refer to the same parts in the several views.

Referring to the drawings, reference character 10 designates a steam drum of a steam generator to which is connected a group of steam circulating tubes 11, a group of downcomer tubes 12, and one or more steam outlet nozzles or connections 13. A main feed water pipe 14 extends longitudinally through the lower portion of the drum and is secured by U bolts 15 to supporting brackets 16 as shown in Figs. 1 to 3 of the drawings. The pipe 14 is provided with flanged noz-

zle connections 17, 18 and 19, 20 respectively, at points adjacent the opposite ends of the drum. Also extending longitudinally through the drum is a chemical feed pipe 21 which in operation 5 discharges through a plurality of small orifices 22 into a drain trough 23, which is disposed in the lower central portion of the drum, and is supported by upright brackets 24. Connected to the nozzles 17, 18 and 19, 20 are vertically extending manifold pipes 25, 26, 27 and 28 respectively, which are disposed adjacent opposite sides of the drum. These manifold pipes are closed at their upper ends by caps 29 and are arranged to distribute fresh feed water to four groups of vertically spaced horizontal feed tubes 30, 31, 32 and 33 which extend longitudinally of the drum from the manifold pipes, to which they are respectively connected, to a point midway between the ends of the drum. The free ends of these tubes 10 are closed by plugs or caps, not shown, and in the sides of the tubes are spaced orifices 34 (Fig. 6).

Between the tubes 30, 31, 32 and 33 and the drum wall, are groups of vertically arranged spaced channel members 35 and 36 respectively, which are secured adjacent their lower ends to support members 37 by bolts 38. The members 37 rest upon short transverse plates 39 which are welded to the wall of the drum (Fig. 4) and are secured to the adjacent channel members by rivets 44. At their upper ends, the channels 35 and 36 are secured respectively to longitudinally extending supporting end plates 41 and 42 which are welded to the drum wall. The channels 35 and 36 are curved to conform with the contour of the inner cylindrical surface of the drum, and they are spaced a short distance therefrom as shown in Fig. 3. The group of channels at the left of the drum as seen in Fig. 1, is somewhat longer than the group of channels at the right. Certain of the channel members are provided with a plurality of spaced bosses 43, which are drilled and tapped to receive the threaded ends of washer assembly supporting bolts 45. These bolts 45 and the bosses support oppositely disposed banks of longitudinally extending trays or reservoirs 46 and baffles 47 in operating relationship with the channel members and the groups of feed tubes 30, 31, 32 and 33.

50 The trays 46 have upwardly extending sides or weirs 48 and 49. The baffles 47 are inverted channels as shown, and are disposed in spaced relationship to the trays below with one leg 50 between the sides of the trays 46 with the lower 55 edge below the upper edge of the tray sides and with the other leg 51 shorter than the leg 50 and disposed beyond the tray side 49. The tubes 30, 31, 32 and 33 are disposed adjacent the inner face of the side 48 of the trays 46 and are welded 60 at spaced intervals to the upper part of the side

48. The bolts 45 extend through openings in both legs of the baffles 47. The trays 46 are supported by the bolts through supporting lugs 52 which are welded to the outer face of side 49 of the trays 46, and lugs 53 which are welded to the sides of the feed tubes at their lower ends and have spacing sleeves 54 welded to their upper ends, the length of these sleeves being such that the legs 50 of the baffles 47 are disposed in the desired positions intermediate the feed tubes and the sides 49 of the trays. A spacing sleeve 55 extends between the legs 50 and 51 of the baffles 47, and this sleeve passes through openings in the lugs 52 which are welded to the tray sides 49. With this arrangement, the bolts 45 support the entire washer assembly on the channel members 35.

Below the lowermost trays 46 of each group of trays and adjacent the lower ends of the channel members 35 and 36 on both sides of the drum 10, are horizontal longitudinally extending plates 56 which are supported by brackets 57 secured to the transverse plates 39. These plates extend from a point adjacent the channel members to a point beyond the trays 46 as shown in Fig. 4. Spanning the space between the plates 56, is a floor or substantially horizontal partition comprising plates 59, 60 and 61, which extend longitudinally of the drum for the length of the washer assembly. These floor plates 59, 60 and 61 are supported by a plurality of spaced transverse members 62 which are secured at their ends to the plates 39 (Fig. 3), and brackets 63, 64 and 65 which are secured to the members 62. As shown, the plates 59 and 61 are inclined toward the center of the floor to cause the feed water and condensate to flow toward the center of the floor. Spaced along the longitudinal center line of the drum, are a plurality of drain pipes 66 which lead from the center of the floor to the trough 23 in the lower portion of the drum.

In the form shown, steam drying means are disposed in the path of the steam after it flows from the washing means. Any suitable means may be employed for drying the steam, but preferably a plurality of closely spaced plates are employed which are shaped or spaced or both, to cause the steam to change its direction of flow more or less abruptly to eliminate entrained moisture therefrom. The drying means shown comprises a row of spaced, intermeshing acute angled plates 67 (Figs. 1 and 3) which are supported by the floor plates 60 and are secured at their upper ends to vertically inclined plates 68 which are attached to brackets 69. The bracket 69 for the left hand group of dryer plates 67 (Fig. 1) is secured by bolts 70 to a fixed supporting bracket 71 adjacent the upper ends of the channel members 35, while the brackets 69 for the right hand group of dryer plates 67 is secured by bolts 72 to a fixed bracket 73 adjacent the upper ends of the channel members 36. Perforated plates 74 extend between and are secured to the brackets 71 and 73. These plates are inclined to the horizontal toward the center of the drum. The washing and drying apparatus is separated from the ends and lower portion of the drum by end plates 75 which are suitably secured to the drum and to the floor thereby providing a compartment in the drum for the washing and drying apparatus. Each plate 75 has an access door 76 for purposes of inspection and repair.

In operation, a supply of relatively wet steam continually enters the drum in jets through the steam circulators 11. The channel members 35

are disposed opposite the ends of the circulator tubes, and the mixture of steam and water issuing from these tubes impinges upon the channel walls, whereby a substantial portion of the entrained water will be removed from the steam, and will drain down the walls of the channels to the body of circulating water in the lower portion of the drum, it being understood that the channel members are not closed at their lower ends as they are at their upper ends. The steam which has thus been freed of entrained boiler water by the channels 35 flows through the spaces between the sides of adjacent channels, and enters the tray assembly through the spaces between adjacent upper and lower trays as indicated by the flow arrows in Fig. 6. Fresh feed water which is discharged continuously through the orifices 34 in the feed tubes, fills each tray 46 and flows over the top of the tray side 49 and collects on the floor, whence it is conducted by the drain pipes 66 to the drain trough 23 adjacent the bottom of the drum. The water flows across the trays from the feed pipes to the sides 49. The steam flows across the trays with the water thereon, but is forced under the surface of the body of flowing water on each tray by the leg 50 of the baffle 47, the lower end of which is submerged in the water on the tray. The steam flowing at a relatively low velocity is thus brought into intimate contact with fresh feed water flowing in the same direction, and any entrained boiler water or moisture of an undesirably high solid concentration will be removed from the steam and replaced by the fresh feed water of a low solid concentration.

That portion of the steam which is released in the drum and does not directly enter the washing trays adjacent the channels 35 will flow downwardly to the space between the water level and the floor and will flow through this space to the open lower ends of the channel members 35 at the opposite side of the drum. This steam will then enter the washing tray assembly adjacent the channels 36 and the washing process will be the same as previously described. The washed steam from the washing trays will flow through the restricted lanes between the plates of the drying apparatus 67, and in its passage therethrough entrained moisture will be removed both by impingement against walls of the angle members, and by centrifugal force resulting from the abrupt changes in direction of flow the steam is required to make. The water thus removed from the steam will drain down the walls of the plates 67 and will collect on the floor and will flow into the drains 66. The steam which is now in a relatively dry condition collects in the steam space 80 between the drying means and thereafter flows through the perforated distributing plates 74. The passage of the steam through a multiplicity of small perforations in the plates 74 has a final drying effect on the steam before it leaves the drum through the steam outlets 13. The perforations also cause the steam to flow evenly across and out of the washer and the drying means.

With this arrangement, it will be perceived that the steam is washed by causing it to flow through a body of fresh feed water which flows in the same general direction as the flow of steam and that practically the entire washer area is available for steam flow, whereby the relative velocity of steam and water flow is very low which provides a longer time of contact between the

steam and water, resulting in improved washing action.

If desired, steam or a mixture of steam and water may be introduced into the drum opposite the channel members 36, similarly to the manner it is introduced through the tubes 11 opposite the channels 35. Additionally, the drying means may be omitted if desired, or any other type or kind of drying means may be utilized. Other changes may be made in the form, location and relative arrangement of the several parts of the apparatus disclosed, without departing from the principles of the invention, which is not to be limited excepting by the scope of the appended claims.

What is claimed is:

1. Apparatus for washing steam comprising enclosing means, a tray disposed in said enclosing means, a supply pipe in the tray at one side thereof and fixed thereto, means for supplying water to said pipe, the pipe having apertures therein through which water flows therefrom and through the tray, supporting lugs secured to the pipe, an inverted U-shaped baffle above the tray and in spaced relationship thereto and having a leg extending into the water in the tray, supporting lugs secured to the opposite side of the tray, means for supplying steam to the tray at the supply pipe side thereof, and means engaging said lugs and the legs of the baffle for supporting the tray and baffle.

2. Apparatus for washing steam comprising enclosing means, a tray disposed in said enclosing means, a supply pipe in the tray at one side thereof and fixed thereto, means for supplying water to said pipe, the pipe having apertures therein through which water flows therefrom and through the tray, supporting lugs secured to said pipe and having a spacing sleeve thereon, an inverted U-shaped baffle above the tray and in spaced relationship thereto and having one leg extending into the water in the tray intermediate the pipe and the opposite side thereof and the other leg disposed beyond the opposite side of the tray, lugs on the opposite side of the tray, spacing means between the legs of the baffle, threaded means extending through the legs of the baffle, said lugs and spacing sleeve for supporting the tray and the baffle, and means for supplying steam to the tray at the supply pipe side thereof.

3. Apparatus for washing steam comprising means forming an enclosure, means for delivering steam to a portion of the interior of the enclosure, a plurality of superposed trays disposed in spaced relationship and positioned to receive steam at one side portion thereof from said portion of the enclosure, means for continuously delivering water to said one side portion of the trays for flow thereover to the other side portion thereof, the bottom of a tray forming the top of a steam passage between the tray and the tray immediately below, which passage is in communication with said portion of the interior of the enclosure, and a baffle member extending downwardly from the bottom of a tray into the water in the tray below to cause the steam to flow from said passage into and through the water on the tray below and beyond said member and in substantially the same direction with the water toward the other side of the tray.

4. Apparatus for washing steam comprising

means forming an enclosure, spaced, substantially vertically disposed channel members having the channel portion thereof opening into a portion of the interior of the enclosure, means for delivering steam into the channel portion of said channel members for impingement therewith and thence into said portion of the enclosure, a plurality of superposed trays disposed in spaced relationship and positioned to receive steam at one side portion thereof from said portion of the enclosure, means for continuously delivering water to said one side portion of the tray for flow thereover to the other side thereof, and means disposed above the tray in spaced relationship thereto to provide a steam passage above the tray in communication with said portion of the enclosure and having a baffle member extending downwardly therefrom into the water on the tray to cause the steam to flow from said passage into and through the water on the tray below and beyond said member and in substantially the same direction with the water toward the other side of the tray.

5. Apparatus for washing steam comprising means forming an enclosure, spaced, substantially vertically disposed channel members having the channel portion thereof opening into a portion of the interior of the enclosure, means for delivering steam into the channel portion of said channel members for impingement therewith and thence into said portion of the enclosure, a plurality of superposed trays disposed in spaced relationship and mounted on said channel members, the trays being positioned to receive steam from said portion of the enclosure, means for continuously delivering water to said one side portion of the tray for flow thereover to the other side thereof, and means disposed above the tray in spaced relationship thereto to provide a steam passage above the tray in communication with said portion of the enclosure and having a baffle member extending downwardly therefrom into the water on the tray to cause the steam to flow from said passage into and through the water on the tray below and beyond said member and in substantially the same direction with the water toward the other side of the tray.

6. Apparatus for washing steam comprising means forming an enclosure, means for delivering steam to a portion of the interior of the enclosure, a plurality of superposed trays disposed in spaced relationship and positioned to receive steam at one side portion thereof from said portion of the enclosure, means for continuously delivering water to said one side portion of the trays for flow thereover to the other side portion thereof, the bottom of a tray forming the top of a steam passage between the tray and the tray immediately below, which passage is in communication with said portion of the interior of the enclosure, and a U-shaped baffle mounted on the bottom of a tray, one leg of the baffle extending into the water on the tray below to cause the steam to flow from said passage into the water on the tray and in substantially the same direction therewith toward the other side of the tray, the other leg of the baffle extending downwardly outside the tray below and adjacent said other side of the tray.

MARTIN FRISCH.
